INVENTOR

Frank A. Byram,
By his Attorney,
Wm. Sowell.

UNITED STATES PATENT OFFICE.

FRANK A. BYRAM, OF PHILADELPHIA, PENNSYLVANIA.

DESIGN FOR TRIMMING.

SPECIFICATION forming part of Design No. 23,885, dated December 25, 1894.

Application filed November 10, 1894. Serial No. 528,424. Term of patent 3½ years.

To all whom it may concern:

Be it known that I, FRANK A. BYRAM, a citizen of the United States, residing at Germantown, (Philadelphia,) in the county of Philadelphia and State of Pennsylvania, have invented a certain new and useful Design for Trimming for Ladies' Underwear, of which the following is a specification.

My invention has for its object the provision of a new and original design for trimming for ladies' underwear of the character hereinafter fully described and illustrated in the accompanying drawings, wherein—

Figure 1 is a front view, and Fig. 2 a view 15 of the back of trimming.

As shown in said drawings, my design consists of a chain backed trimming the heading of which is of plain inlay or gimp backed by four parallel straight rows of chain; a row 20 of pendants or pillars depending from such heading, composed of groups of four double threads arranged in rather loose order and having intervening ribbon-spaces; a similar row of chain sustained by the lower portions 25 of said pendants or pillars below which the ends of the latter extend and sustain the top-most one of a series of three parallel rows of approximately round wheel-like parts, the other two rows being suspended from the first 30 mentioned row, and the one from the other, through the medium of double loops, as shown. These wheel-like parts, or those of each of the respective rows, are backed by three rows of chain, there being, therefore, nine rows of 35 chain for the whole lot of wheels. The wheels of each row are composed of two lengths of

yarn, at distances apart corresponding with the diameter of the circles to be formed, which are doubled or inverted inwardly, toward each other, at intervals, the doubled portions of one 40 overlapping those of the other, thus completing the circle, in which condition they are backed by two rows of chain which follow the outline of each such row, having depressions 45 therein corresponding with the inturned portions thereof, and have loops cast around and binding the yarn thereto, while the middle row of each set of three rows of chain is straight throughout and extends lengthwise of the trimming across the central openings 50 of the wheels of the respective rows, merely touching at the junctures of the doubled portions of the yarn which forms the same, around which doubled portions are thrown loops of this central chain, too, which chain, 55 with threads radiating therefrom and extending out to the rims of such wheels, forms the spokes of the latter, certain of which threads being passed or caught under the loops of the upper row of chain of each set which appears 60 on the face of the wheels and draped or festooned along the upper edge of the face of each row of the same.

What I claim as my invention is—

The design for trimming for ladies' underwear substantially as shown and described.

In testimony whereof I have hereunto set my hand this 31st day of October, A. D. 1894.

FRANK A. BYRAM.
